UNITED STATES PATENT OFFICE.

MARY DONALD, OF NEW YORK, N. Y.

VEIL.

1,020,083.

Specification of Letters Patent. Patented Mar. 12, 1912.

Application filed May 19, 1911. Serial No. 628,237.

To all whom it may concern:

Be it known that I, MARY DONALD, a citizen of the United States, and a resident of Brooklyn borough of the city of New York, 5 county of Kings, and State of New York, have invented a certain new and useful Veil, of which the following is a specification, the same being a full, clear, and exact description of the invention, such as will 10 enable others skilled in the art to which it appertains to make and use the same.

This invention relates to articles made of lawn or lace or other fabric or material adapted for ladies' use, and in particular 15 to a piece of gauze, grenadine, lace, crape, or other similar fabric used to cover the face and hair as a protection against the sun or wind, and adapted to be attached to the bonnet or hat, and which embodies cer- 20 tain novel features of construction, and combination and arrangement of parts, of simple construction and efficient in operation.

In order to enable the invention to be 25 fully understood, I shall proceed to explain the same by reference to the drawings, illustrative of one embodiment of the invention, which accompany and form a part of this specification, and in which—

30 Figure 1 represents an elevation of an ordinary veil before being made up according to my invention: Fig. 2 is an elevation of the same after my invention is embodied therein: Fig. 3 is a view of the veil as used 35 in practice: Fig. 4 is a view in detail of a way of folding the edge of the veil: and Fig. 5 is a partial view of another veil constructed according to my invention.

Like letters of reference indicate like 40 parts in all the views.

Referring particularly by reference characters or symbols to the drawings, A denotes the body of a veil, and A' the edge or hem, or lower portion, as used in practice, of the central part thereof, which edge is preferably made so as to be thicker than the rest of the said veil. At certain points at a substantial distance from the center the veil is fulled or Shirred, or made in small 45 puckers, plaits, folds or gathers, as for example, in the present instance, by making a bend or fold α at the edge of the veil, and another bend or fold α' ordinarily overlapping the former one. These folds or bends 50 are preferably sewed, or otherwise attached together, whereby the gathers α^2 are formed

in the central portion of the body of the veil adjacent to the said bends or folds. The two lateral ends or edges of the part A' are constructed and arranged so as to 60 meet or overlap, in practice, at the back of the neck, and may be, and preferably are, securely, but detachably, held together by attaching means of any desired character, as, for example, the fastenings α^3 , which 65 may be snap buttons; or, if desired, hooks and eyes, or other securing means, may be used. The upper part of the veil, consisting of the central portion of the body thereof, and also of the end, or wing-like, 70 portions of the said veil, preferably extending off at each side of said engaging edges at an angle from the central portion of the said body, may then be tied, in use, around the hat, as is shown in Fig. 3.

The edge A' of the central portion of the body of the veil may be integral, as by having the edge folded over, as a hem, or else the thickened edge may be woven in the veil; or, if preferred, the said edge may consist of a separate piece of fabric attached to, or laid over, the boundary line of the veil; and, if desired, the edge may be ornamental in form and made as a collar, as shown at A² in Fig. 4.

In each of the above examples of my invention, it will be observed that the lower part of the veil encircling the neck is thicker than the body thereof that lies over the face. In some cases, I prefer to extend the hem or 90 thickened edge of the veil from each side of the said meeting or engaging edges, as A¹⁰ in Figs. 2 and 3, which hem or edge, or thickened lower part of the veil, will, in such case, form a boundary of the end portions of the veil which extend off or away, at each side of said meeting edges, at an angle, from the central portion of the body thereof. In cases like those just referred to, the two edges A¹⁰ will, when the veil is 100 applied to the head, preferably lie adjacent to each other; or, if desired, one of such edges may be placed over the other, and the two may be securely, but detachably, held together by fastening devices, as α^3 .

It will be seen that my invention comprises an encircling neck band, used in combination with any kind of face veiling now on the market, or that may be made specially for the purpose of my invention, 110 the said band being either integral with the veil and formed in the veil in the manu-

facture of the same by strengthening or stiffening the edge thereof, or being of any suitable separate material, plain or fancy, that may be attached to the veil so as to 5 either abut, or lay over, what is intended as the lower edge of the veiling.

Obviously, my banded veil may be either hand or machine made.

The banded edge of the veiling can be 10 fashioned to fit any size of neck by means of the turned corners or bends which may be positioned a certain distance, as a number of inches, apart according to the required measurement, my improved veils being 15 pref- erably made and sold in various sizes in order to approximately fit the necks of stout or slender persons. The said corners or bends forming the engaging edges, may be made with or without cutting the ma- 20 terial, and may be formed in contour ac- cording to the taste of the public, as by being angular, square, round, gathered or fulled, etc., in conformation. The banding may be either a plain straight band, or 25 shaped ornamental in collar fashion. In the former case, it may continue up the back of the head and all around the head, in prac- tice, if desired. In the latter case, in order to obtain the desired encirclement of the 30 neck, it will only be necessary to shape the turned corners or meeting edges on the nar- row selvage of the veiling at the required distance apart, and attach the same to the collar. 35 I do not wish to limit myself as to the style of work, or the material used, in the manufacture of my improved veils; and the fastenings used in connection therewith may be of any useful or ornamental kind. If 40 preferred, materials, such as ribbon, velvet, silk ribbon or novelty trimmings, boning, wiring, etc., can be put on, or attached to the veiling in order to form the strength-

ened edge or band thereof in the manner well known to those skilled in the art.

45

The gathers, folds or Shirring of the body of the veil, at the engaging ends of the veiling, are for the purpose of providing sufficient fullness of the veil, when in use, to cover the face without being too tightly 50 drawn over it, while the two ends of the veil extending at an angle from the central portion thereof, allow the said ends to completely cover the hair at the back of the head. In practice, by merely unfastening 55 the lower edge of the veil behind the neck, the veil may be easily raised from the face and thrown up on the hat, whenever de- sired, without detaching the veil: and the latter may be readily restored again to its 60 normal position enveloping both the face and the hair, and, in fact, the entire head beneath the hat.

I wish it to be understood that I do not desire to be limited to the exact details of 65 construction shown and described herein, for various modifications will occur to a person skilled in the art.

What I claim as my invention, is:—

A veil having a border at one longitudi- 70 nal edge, said edge at two points at a sub- stantial distance from the center folded over upon itself and suitably secured at such folded points to provide lateral bordered edges, whereby a fullness at the point of the 75 folds is provided, and fastening devices for securing said lateral edges together when on the wearer.

In testimony of the foregoing specifica- 80 tion, I do hereby sign the same in the city of New York, county and State of New York, this 15th day of May, 1911.

MARY DONALD.
